UNITED STATES PATENT OFFICE.

MEDERIC L. FITZPATRICK, OF NEW YORK, N. Y.

BRISTLE COMB.

Application filed August 10, 1922. Serial No. 580,939.

To all whom it may concern:

Be it known that I, MEDERIC L. FITZPATRICK, a citizen of the United States of America, and a resident of New York, N. Y., 5 have invented new and useful Improvements in Bristle Combs, which invention is fully set forth in the following specification.

This invention relates to combs, and more particularly to a comb provided with brush bristles to the end that both the combing and brushing action on the hair may be simultaneously accomplished with the same instrument. The object of the invention is to provide a comb structure which will serve 10 the ordinary purposes of a comb to straighten or arrange the hair strands approximately parallel with each other, and at the same time and by the same operation brush the individual hairs so as to effectively remove 15 dust or dirt therefrom and impart the gloss and finish to the tresses resulting from the ordinary use of a brush.

With this object in view, the invention consists of a body or back portion composed 25 of any suitable material, in which back portion is arranged a series of teeth each of which teeth supports a mass of brush bristles radiating from the teeth.

The inventive idea is capable of receiving 30 a variety of mechanical expressions, one of which, for the purpose of illustrating the invention, is shown in the accompanying drawings, in which—

Fig. 1 is a side elevation;

Fig. 2 is an end elevation; and

Fig. 3 is a diagram of one of the teeth.

In said drawings, 1 indicates the back or body portion composed of any suitable material, as wood, hard rubber, celluloid or 40 the like, and 2 indicates the teeth mounted in said body portion in any suitable or desired manner. These teeth may be variously formed, but as here shown they consist of a plurality of wires spirally twisted together 45 with a continuous mass of brush bristles 3 secured between the twists of the wires. These wires, with the bristles secured thereto, are cut in suitable lengths to form the teeth. Preferably, however, each tooth is 50 made of a single piece of wire bent sharply at its central portion and then the two portions of the wire spirally twisted together

with the brushing bristles enclosed in the twists thereof. This forms the tip end of each one of the teeth of a smooth rounded 55 portion of the wire, as shown in Fig. 3, the two ends of the wire forming the portion of the tooth that is anchored or set into the back of the comb.

It will be observed that the teeth are so 60 spaced and the length of the bristles are such that the bristles of one tooth overlap the bristles of the next adjacent tooth and that at the outer end of the tooth the bristles are shortened so that the mass of bristles tapers 65 toward the outer end of the tooth in a conical form. In use the teeth themselves serve, when drawn through the hair, to arrange the strands of hair parallel as with an ordinary comb and at the same time, i. e., simultaneously with the combing action, the brush bristles coat with each other to impart an efficient cleansing and brushing action to the individual hairs.

What is claimed is:—

1. A comb comprising a back portion, a series of teeth arranged along said back portion, and brushing bristles on said teeth.

2. A comb comprising a back portion, a series of uniformly spaced teeth arranged 80 along said back portion, and brushing bristles radiating from the teeth.

3. A comb comprising a back portion, a series of uniformly spaced teeth mounted on 85 said back portion and projecting at right angles therefrom, and brushing bristles radiating from said teeth parallel with the back portion, the bristles on one tooth overlapping those on the adjacent tooth.

4. A comb comprising a back portion, a 90 series of teeth arranged along said back portion, and brushing bristles on said teeth, the bristles on adjacent teeth overlapping for a part of the length of the teeth and then tapering conically to the extreme outer end of 95 each tooth.

5. A comb comprising a back portion, a series of teeth arranged on said back portion, said teeth consisting of twisted wire and brushing bristles secured in the twists 100 of the wire.

In testimony whereof I have signed this specification.

MEDERIC L. FITZPATRICK.
